J. J. FITZGERALD,
REFLECTING SIGNAL OR ADVERTISING MEDIUM,
APPLICATION FILED JUNE 18, 1918.

1,302,782.

Patented May 6, 1919.

Inventor,
John J. Fitzgerald,
By *Raymond J. Fitzgerald*

His Attorney.

UNITED STATES PATENT OFFICE.

JOHN J. FITZGERALD, OF LOS ANGELES, CALIFORNIA.

REFLECTING SIGNAL OR ADVERTISING MEDIUM.

1,302,782.

Specification of Letters Patent.

Patented May 6, 1919.

Application filed June 18, 1918. Serial No. 240,574.

To all whom it may concern:

Be it known that I, JOHN J. FITZGERALD, a citizen of the United States, residing at Los Angeles, in the county of Los Angeles 5 and State of California, have invented new and useful Improvements in Reflecting Signals or Advertising Mediums, of which the following is a specification.

This invention relates to reflecting signals 10 or advertising mediums, and it has for its object to provide improved means of this character constituting in the main an improvement over or departure from the subject of another application for U. S. Letters 15 Patent filed by Alfred H. Barnes and myself, May 22, 1918, Serial No. 236,019, for reflecting signals or advertising mediums. The invention in that case consisted in the main in a device adapted to be stationed 20 adjacent to highways, in particular, and comprising a reflector, a transparent member forward of the reflector and bearing insignia or symbols adapted to be outlined and rendered visible by light rays projected forwardly from the reflector, and means adjacent to the reflector for modifying rays of light received from passing road vehicles or other sources, prior to the projection of such rays of light by the reflector. Thus, 25 30 white or yellow rays received from automobile head lights could be given a violet tinge and then projected from the reflector around the wordings or symbols upon the transparent plate, and the latter caused to stand out boldly in relief in the midst of such violet rays.

The present invention, while it relates to the same subject matter, deals only with the means for modifying the light rays. 40 The general combinations of members and features are claimed in said other application, and the present invention, as stated, relates to such combination modified to include a particular means for modifying the 45 light rays received and to be reflected by the reflector.

The invention has for its object to provide improved means of the general character stated which will be superior in point of 50 relative simplicity and inexpensiveness of construction and organization, compactness in form, facility in construction and assemblage, and general efficiency and serviceability.

55 The invention consists in the novel and

useful provision, formation, combination, association, and relative arrangement of parts, members and features, all as herein-after described, shown in the drawing, and finally pointed out in claims.

60

In the drawing:

Figure 1 is a front elevation of means embodying the invention;

Fig. 2 is a central vertical sectional view of the same, taken upon the line x^2-x^2 , 65 Fig. 1, parts remaining in elevation;

Fig. 3 is a view in separate detached position of a particular feature of the present improvement or invention; and,

Fig. 4 is a similar view of a further feature utilized in embodying the invention. 70

Corresponding parts in all the figures are designated by the same reference characters.

Referring with particularity to the drawing, 5 indicates a reflector and 6 a transparent plate disposed forwardly thereof, of signaling or advertising means provided with a support or upright 7, all in accordance with the present invention. 9 designates writings, symbols, or the like upon the 80 transparent plate 6, which are adapted to be outlined, limned or thrown into relief and rendered visible by rays of light directed forwardly through the transparent plate 6 by the reflector 5, being first received from 85 the lamp of a passing vehicle or other source of light, which rays pass inwardly to the reflector 5 through the transparent plate 6. These rays strike the means A, the particular feature of the present invention, which 90 means modify such rays prior to their striking the reflector 5, whereupon such modified rays, changed, we will say, from one color to another, are reflected by the reflector 5 and projected forwardly through the transparent plate 6 so as to outline and cause to be legible the symbols or writings or the like 95 9.

The means A in the present case comprises a bulb, preferably a hollow glass bulb 10, 100 which is blown or formed with a hollow neck 11 in communication therewith, which neck is received in a split ring socket 12 having prongs or feet 13 which are soldered or otherwise attached to the central portion 105 of the housing 5^a of the reflector 5. The surface of the bulb 10 is colored or otherwise transformed so as to cause it to modify the rays which impinge upon it and thence are directed to the reflector 5 and from it 110

are projected through the transparent plate 6 in the manner stated.

It is manifest that detail changes and variations may be made, in practising the 5 invention, with respect to the particular formation, construction, combination and inter-relation of parts, members and features, herein described and pictured in the drawing, all without departing from the true 10 spirit of the invention and a fair interpretation thereof.

Having thus disclosed my invention, I claim and desire to secure by Letters Patent:

1. In means of the character disclosed, a 15 reflector, a transparent plate, and means for modifying light rays received through the plate and to be reflected by the reflector back through the plate, such means comprising a hollow bulb provided with a neck, and 20 means for positioning the same forwardly of the reflector by engagement with said neck.

2. In means of the character disclosed, a 25 reflector, a transparent plate, and means for modifying light rays received through the plate and to be reflected by the reflector back through the plate, such means comprising a hollow bulb provided with a neck, and means for positioning the same forwardly of the reflector by engagement with 30 said neck; said last named means comprising a socket adapted to receive said neck.

3. In means of the character disclosed, a 35 reflector, a transparent plate, and means for modifying light rays received through the plate and to be reflected by the reflector back through the plate, such means comprising a hollow bulb provided with a neck, and

means for positioning the same forwardly of the reflector by engagement with said neck; said last named means comprising a 40 socket adapted to receive said neck; said bulb and said neck being hollow and in communication with each other.

4. In means of the character disclosed, a reflector, a transparent plate, and means for modifying light rays received through the plate and to be reflected by the reflector back through the plate, such means comprising a hollow bulb provided with a neck, and means for positioning the same forwardly 45 of the reflector by engagement with said neck; said last named means comprising a socket adapted to receive said neck; said socket having projections adapted to be secured to the housing of said reflector.

5. In means of the character disclosed, a reflector, a transparent plate, and means for modifying light rays received through the plate and to be reflected by the reflector back through the plate, such means comprising a hollow bulb provided with a neck, and means for positioning the same forwardly of the reflector by engagement with 50 said neck; said transparent plate being provided with symbols, characters or the like, adapted to be outlined by the reflection of modified light rays from said reflector.

In testimony whereof I have signed my name to this specification in the presence of two subscribing witnesses.

JOHN J. FITZGERALD.
